UNITED STATES PATENT OFFICE.

WILLIAM D. OGLESBY, OF MIDDLETOWN, OHIO, ASSIGNEE TO THE O. K. PAPER PAIL COMPANY, OF MIDDLETOWN, OHIO, A CORPORATION OF OHIO.

EGG CARTON.

Application filed May 29, 1922. Serial No. 564,499.

To all whom it may concern:

Be it known that I, WILLIAM D. OGLESBY, a citizen of the United States, and a resident of Middletown, in the county of Butler and the State of Ohio, have invented certain new and useful Improvements in Egg Cartons, of which the following is a full, clear, and exact description, reference being had to the accompanying drawings, forming part 10 of this specification.

The object of my invention is to provide a carton made from an integral blank of suitable cardboard material, which can be readily and easily folded to form protective 15 compartments for the single eggs, in which the partitions when the carton is set up will suitably brace each other and the sides of the carton and resilient walls will be provided for each egg. I also provide a construction which, when the ends of the carton 20 are secured together, can be easily nested for shipment with the transverse partitions opened out.

My carton is especially designed for the 25 convenience of the retailer in packing of eggs for delivery to the purchaser and is intended to be sold to the retailer in nested condition with the sides and ends set up and properly locked together, leaving to the 30 retailer merely the folding in of the transverse partition members and the top, but it will be obvious that when desired the cartons can be manufactured and sold in flat knock-down condition to be completely set up by the retail dealer and the ends locked together by any suitable cleat or fastener, such as are in common use for securing 35 papers together.

The invention consists of that certain novel 40 construction of blank cut and scored for folding as hereinafter to be more particularly pointed out and claimed.

In the drawings,

Figure 1 is a plan view of the blank cut 45 and scored to obtain the proper folds for the carton.

Figure 2 is a perspective view of the carton ready for use with the top cover open.

Figure 3 is a cross section on the line 50 3—3 of Figure 2.

Figure 4 is an end view of the cartons showing method of nesting for shipment.

A sheet of suitable cardboard is cut and scored as shown in Figure 1 to form side

walls 1, 2, and bottom sections 3, 4, with an 85 intermediate portion of sections 5 and 6 adapted to fold together on the score line 7 to form a central longitudinal partition for the carton.

Integral with one of the sides 2 are a series 80 of tongues 8 designed to form the transverse partitions to co-operate with the central partition in providing separate individual compartments for each egg. In the present instance I have designed my carton 85 to hold a dozen eggs and in this event, as shown, there will be five of these tongues, but of course it will be understood that the length of the carton and the number of transverse partitions will be governed by the 70 number of eggs the box is designed to hold.

These tongues are provided with a longitudinal score line 9, and diagonal score lines 10, 10, and for a short distance from the meeting point of these score lines 10 the 75 cardboard is completely severed or cut through as indicated by the full lines in Figure 1. This is for convenience in folding together the outer portion of each tongue in order that when folded together on the lines 80 9, the tongues may be folded across the carton on the score lines 12 and caused to engage each its respective slot 13 cut in the longitudinal partition 5, 6. The outer ends of the tongues are cut on a bevel, as shown 85 at 14, to engage the side wall 1 of the carton, as will be described. This side wall 1 is formed with the cover section 15 with a longitudinal flap 16 scored for folding. The cover section is also provided with end flaps 90 17, 18.

The sides 1 and 2 are formed with end flaps 19, 20, and 21, 22, and the score lines 23 for these flaps are slightly diagonal in order to allow for the flaring sides when the 95 carton is folded. For the formation of the ends of the carton the bottom section 3 is provided with an end flap 24 of the size of the end of the carton so as to give some flare to the side walls when the carton is erected, 100 and the bottom section 4 is at the opposite end formed with a similar flap 25, while to more effectively close the ends, the bottom section 3 has at the opposite end from the wide flap 24, a narrower flap 26 and the bottom section 4, a similar flap 27.

To erect the carton, the sides 1 and 2 are raised, the partition members 5 and 6 folded

together, the end flaps 24 and 25 raised, and these flaps with the end flaps 19, 21 and 27 at one end and flaps 20, 22, 26 at the other, secured together by staples 28.

5 The carton will then be in condition for shipment and they can be nested together as many as desired, as shown in Figure 4.

To set up for the separate eggs, the tongues 8 are folded together to each form 10 a double strip and then folded over to engage each in its respective slot 13 in the longitudinal partition, the beveled ends 14 fitting against and bracing the side wall 1 of the carton. The carton is then ready 15 for the eggs, the top is folded down, and the flaps 16, 17, 18, tucked in and the package is ready for delivery.

It will be noticed that the partition walls are all double and formed by folding together sections of the cardboard, so the walls 20 are very resilient and hold the eggs separate from each other by these double walls under a spring tension, so that there is no danger of breakage.

25 Instead of fastening the ends together with staples, of course, other equivalent means may be employed, and as already set forth, the cartons may be sold entirely knocked-down and fastened together at the 30 ends by the user and generally so long as the novel principles of my construction are involved as set forth in the claims that follow, I do not desire to be limited to the details of the construction by reason of any 35 failure to mention obviously equivalent constructions.

Having thus described my invention, what I claim as new and desire to secure by Letters Patent, is:—

40 1. A carton formed from a single blank of suitable cardboard material cut and scored to form bottom, sides, and ends, with the bottom scored to fold lengthwise to form a longitudinal partition and with side extensions to form transverse partitions interlocking 45 with the longitudinal partition to provide a series of individual compartments.

2. A carton formed from a single blank of suitable cardboard material cut and scored 50 to form bottom, sides, and ends, with the bottom scored to fold lengthwise to form a longitudinal partition and with side extensions, each extension folded lengthwise, to form transverse partitions interlocking with the longitudinal partition to provide a series 55 of individual compartments.

3. A carton formed from a single blank of suitable cardboard material cut and scored to form bottom, sides, and ends, with the bottom scored to fold lengthwise to form a longitudinal partition and with side extensions to form transverse partitions, the bottom fold provided with transverse slots to

receive the side extension and provide a series of individual compartments.

4. A carton formed from a single blank of suitable cardboard material cut and scored to form bottom, sides, and ends, with the bottom scored to fold lengthwise to form a longitudinal partition and with side extensions, each extension folded lengthwise, to form transverse partitions, the bottom fold provided with transverse slots to receive the side extension and provide a series of individual compartments.

5. A carton formed from a single blank of suitable cardboard material cut and scored to form bottom, sides, and ends, with the bottom scored to fold lengthwise to form a longitudinal partition and with side extensions to form transverse partitions interlocking with the longitudinal partition to provide a series of individual compartments, with the ends of the side extensions bearing against the opposite side wall to brace and support the carton.

6. A carton formed from a single blank of suitable cardboard material cut and scored to form bottom, sides, and ends, with the bottom scored to fold lengthwise to form a longitudinal partition and with side extensions, each extension folded lengthwise, to form transverse partitions, the bottom fold provided with transverse slots to receive the side extension and provide a series of individual compartments, with the ends of the side extensions bearing against the opposite side wall to brace and support the carton.

7. A carton formed from a single blank of suitable cardboard material cut and scored to form bottom, sides, and ends, with the end flaps flaring to form a carton wider in cross section at the top than at the bottom, and with the bottom scored to fold inwardly to form sloping walls for a double-walled partition, and said walls transversely slotted, side extensions to form tongues adapted to engage said slots to form transverse partitions with the ends of the tongues bearing against the opposite side wall to brace and support the side wall.

8. A carton formed from a single blank of suitable cardboard material cut and scored to form bottom, sides, and ends, with the end flaps flaring to form a carton wider in cross section at the top than at the bottom, and with the bottom scored to fold inwardly to form sloping walls for a double-walled partition, and said walls transversely slotted, side extensions to form tongues, each tongue folded in itself lengthwise and adapted to engage its respective slot to form transverse partitions with the ends of the tongues bearing against the opposite side wall to brace and support the side wall.

WILLIAM D. OGLESBY.
